SULPHATED AMIDE WETTING, DETERGENT,
AND SUDSING AGENTS

Heinrich Bertsch, Rabenstein, near Chemnitz,
Germany, assignor, by mesne assignments, to
The Hydronaphthene Corporation, Wilmington,
Del., a corporation of Delaware

No Drawing. Application February 28, 1939,
Serial No. 259,006

2 Claims. (Cl. 260—401)

This invention relates to wetting, detergent and sudsing agents consisting of water-soluble salts of sulphuric acid esters of hydroxy alkyl, carboxylic acid amides and to a method whereby such agents may be directly and most efficiently produced. Agents for like and related purposes composed of sulphuric acid esters of amides of higher fatty acid as a class, and also certain specific esters within the class, have already been patented to the applicant in the Bertsch Patent 1,918,373, dated July 18, 1933.

Agents similar to those of the present invention are already known to the art, but those having compounds of unlike chemical structure are inferior in quality in the fields of use in which the instant agents are employed, and those agents of the prior art having compounds of like chemical structure comprise mixtures with an objectionable proportion of other compounds unavoidably or unintentionally present as a result of the specific method by which the agents have been produced, which mixed agents are poor in quality or efficiency as compared with the agents of the present invention.

Under the present invention, agents of the class herein described are produced by a process wherein hydroxy alkyl, fatty acid amides of the proper molecular weight are prepared in a reaction wherein quantitative yields are obtained, the resulting amides thereafter being sulphated and neutralized, thereby producing a product composed of substantially one hundred percent of water-soluble salts of sulphated hydroxy alkyl, fatty acid amides, which products constitute excellent wetting, cleaning and sudsing agents.

Outstanding features of the invention are the avoidance of hydrolysis of the product without using special conditions of treatment, such as low temperatures, thereby producing quantitative yields, and the greater efficiency and extension in fields of use of the substantially pure product. The instant products are quite free of unreacted raw materials, intermediate and split reaction products, which products are present in similar prior art agents.

In accordance with the preferred procedure of the instant process the chloride, bromide or other halide of fatty acids having 8 or more carbon atoms is reacted with hydroxy lower molecular aliphatic amines, and the hydroxy aliphatic radical, fatty acid amides obtained are thereafter reacted with sulphuric acid or other sulphating agent, after which the resulting acid ester is neutralized by means of sodium hydroxide or

other base adapted to produce water-soluble salts.

The fatty acid halogenides used as the initial material in the present process are derived in any suitable manner from the desired fatty acid or mixture of fatty acids having 8 or more carbon atoms in the molecule. These fatty acids may be either saturated or unsaturated fatty acids or hydroxy fatty acids. The fatty acid mixture obtainable from cocoanut oil is preferably used in the instant process, but the individual fatty acids may also be employed. Other suitable sources of fatty acids include palm nut oil and sperm oil. Among the individual fatty acids suitable for treatment, there may be mentioned lauric acid, myristic acid, palmitic acid, stearic acid, oleic acid and ricinoleic acid. Fatty acids of even higher molecular weight than in these examples are suitable for the production of products for use in specific fields, but for general purposes the products derived from the carboxylic acids having from 8 to 18 carbon atoms give best results. Carboxylic acids obtainable from oxidation products of hydrocarbons may be used in specific instances, if such acids are obtainable in a sufficiently pure condition.

The amine component of the present invention is preferably a monohydroxy aliphatic amine of lower molecular weight. However, other hydroxy amines may be employed, such as, for example, monoalkylol amine, dialkylol amine and trialkylol amine. The alkylol radical may be either saturated or unsaturated and the amine may be a mixed amine with alkyl radicals differing in length of carbon chain. In the di- and triamines, one substituent may be a hydroxy alkyl radical, whereas another may be a unsubstituted alkyl radical. Suitable alkyl radicals include ethyl, methyl, propyl and other lower molecular normal and isoalkyl radicals. The hydroxy aliphatic amines react readily with the fatty acid halogenides, the reaction mass being preferably heated somewhat to increase the rapidity of the reaction.

The sulphation of the hydroxy aliphatic, fatty acid amide may be accomplished through the use of conventional sulphating agents, including highly concentrated sulphuric acid, sulphuric acid monohydrate, fuming sulphuric acid, chlorosulphonic acid and anhydro-pyridine sulphonic acid. Depending upon the particular sulphating agent used, the temperature of the reaction may be carried out at room temperature or may be carried out at a slightly elevated temperature, preferably not above 50° C. Cooling may be em-

ployed, but low temperatures are not necessary for effectively accomplishing the sulphation. The quantity of sulphuric acid employed depends upon the nature of the raw material used and the nature of the final product desired. For example, when unsaturated bonds or more than one hydroxy group is contained in the hydroxy aliphatic, fatty acid amide, more than one sulphuric acid ester group may be introduced into the molecule, in which case a larger quantity of the sulphating agent is employed. Furthermore, the sulphation reaction may be carried out in the presence of suitable solvents, including, for example, lower molecular alkyl ethers, such as ethyl, propyl and butyl ethers, pyridine and other tertiary bases. The use of these solvents is particularly beneficial when unsaturated fatty acid radicals are contained in the amide to be sulphonated and it is desired that a single sulphuric acid ester group be introduced in place of the hydroxy radical at the end of the alkyl chain.

Example 1

A fatty acid chloride mixture obtained from a commercial mixture of fatty acids derived from cocoanut oil, in a quantity of 245 kgs. is mixed with 65 kgs. of monoethanol amine and caused to react therewith at slightly elevated temperatures. When the reaction has gone to completion, 275 kgs. of the resulting condensation product are then sulphated by the introduction of 300 kgs. of sulphuric acid monohydrate at room temperature. Thereafter the sulphated ethanol, fatty acid amides are neutralized in conventional manner with sodium hydroxide.

Example 2

As in the foregoing example, the chlorides of cocoanut oil fatty acids are reacted with monoethanol amine. Thereafter 275 kgs. of the condensation product obtained are reacted with 120 kgs. of chlorsulphonic acid in the presence of 200 kgs. of ethyl ether. Next the sulphuric acid esters obtained are neutralized with sodium hydroxide in conventional manner.

The sulphuric acid esters of the hydroxy aliphatic, fatty acid amides of the present invention are preferably employed in the form of their water-soluble salts. For obtaining these salts, the alkali metal hydroxides and other inorganic bases are suitable. Also, organic bases may be employed for the neutralization, compounds such as triethanol amine and triethyl amine being satisfactory. The organic salts are particularly useful in the production of cosmetics, shampoos and the like.

As hereinbefore indicated, the products of the present invention are generally useful as wetting, detergent and sudsing agents. They may be employed to advantage in household operations and in industrial processes of the most varied nature.

They are useful as assistants in the textile, leather and allied industries, also in the pharmaceutical industry and in the preparation of insecticides.

- 5 Although the compounds of the present invention may be satisfactorily used in the absence of additional capillary active or other agents, such compounds may, for the preparation of products for specific purposes, be admixed with other substances of the nature of soaps, higher molecular alcohols, ketones, aromatic sulfonic acids and their salts, sulfonated oils, and organic solvents, including hydrocarbons and halogen derivatives of hydrocarbons.
- 10 15 The outstanding advantage of the present invention, as hereinbefore indicated, lies in the simplicity and effectiveness of the process steps involved, whereby substantially one hundred percent of the organic compounds employed combine in the reaction to form the desired product.
- 20 Therefore, the product is obtained in a state free from other similar reaction products, such as alkylol amine esters of fatty acids, which are lower in efficiency or do not possess the valuable properties of the water-soluble salts of the sulphuric acid esters of the hydroxy alkyl, fatty acid amides. The product is, for example, free of any hydroxy alkyl amine ester of fatty acids either in its free or sulphated form, which products have been present in similar agents prepared in accordance with prior art processes.

It should be understood that the present invention is not limited to the specific substances described or the specific procedure disclosed, but that it extends to all other compounds and equivalent procedures within the scope of the claims appended hereto.

I claim:

1. The process of directly producing water-soluble salts of sulphated hydroxy alkyl, fatty acid amides in a form substantially free of extraneous organic materials, which comprises condensing a monohalogenide of a fatty acid containing at least 8 carbon atoms with a lower 40 molecular monoalkylol amine, thereby obtaining a quantitative yield of a hydroxy alkyl, fatty acid amide, then sulphating said product at the said hydroxy group and neutralizing to produce a water-soluble salt of the sulphuric acid ester of said amide.
- 45 50 55 60 65 70 75 80 85 90 95 100
2. The process of producing wetting, detergent and sudsing agents consisting of water-soluble salts of sulphuric acid esters of hydroxy ethyl, acyl amide, said acyl group having 8 to 18 carbon atoms, which comprises condensing a carboxylic acid monochloride having 8 to 18 carbon atoms with monoethanol amine, sulphating the reaction product at the said hydroxy group and neutralizing with a base adapted to form a water-soluble salt of the sulphuric acid ester formed.

HEINRICH BERTSCH.
